UNITED STATES PATENT OFFICE.

NICOLAS EMILIE MÉTHLIN, OF PARIS, FRANCE, ASSIGNOR TO SCHNEIDER & CIE., OF PARIS, FRANCE, A LIMITED JOINT STOCK COMPANY OF FRANCE.

SMALL-CALIBER GUN.

Application filed April 4, 1925. Serial No. 20,817.

To all whom it may concern:

Be it known that I, NICOLAS EMILIE MÉTHLIN, a citizen of the Republic of France, resident of Paris, France, have invented new and useful Improvements in or Relating to Small-Caliber Guns, which is fully set forth in the following specification.

This invention relates to an apparatus for automatically loading small caliber guns. The apparatus, which is actuated by the recoil and running out of the gun, is characterized essentially by the fact that it comprises a sort of endless conveyor or chain of buckets or troughs which is in continuous motion, and is arranged transversely to the longitudinal axis of the gun and above the latter so that the troughs on the underside of the conveyor form housings, each one receiving automatically, as it passes over a section of the loading member or magazine, one of the projectiles contained in this section, and carries it over an automatic distributor which is also actuated by the alternate recoil and running out of the gun, the said distributor bringing the projectile into line with the bore of the gun and the ramming breech block, for it to be rammed in the known manner into the bore of the gun.

In addition to this essentially characteristic device, the apparatus comprises various other special features which will be hereinafter described, and which are illustrated in the accompanying drawings, which show one special form of construction of the invention applied to an arrangement of conjugated gun barrels in which the recoil of one of the two barrels always causes the other one to run out and vice versa.

Figures 1, 2 and 3 in the accompanying drawings are general arrangement views of the apparatus fitted to an arrangement of conjugated gun barrels.

Figure 1 is a sectional elevation taken along the line 1—1 in Figure 2, which is a sectional elevation taken along vertical planes parallel to the axis of the gun barrels.

Figure 2 is a cross sectional elevation taken along the line 2—2 in Figure 1, that is to say, partly through the conveyor, the

loading member or magazine and the distributor.

Figure 3 is a plan view.

Figure 4 is a sectional elevation of a detail, to a larger scale, taken along the line 4—4 in Figure 2, through the conveyor and a section of the magazine, this section showing the device for automatically feeding the conveyor.

Figure 5 is a sectional elevation of a part taken along the line 5—5 in Figure 4.

Figure 6 is a plan section taken along the line 6—6 in Figure 4.

Figure 7 is a plan section taken along the line 7—7 in Figure 4.

Figure 8 is a section of a part taken along the line 8—8 in Figure 7.

Figures 9, 10 and 11 are sections of parts, taken along the lines 9—9, 10—10 and 11—11 in Figure 4.

Figure 12 is a cross section of a detail, taken through the underside of the conveyor and showing one of the holding troughs of the conveyor which has approached the distributor; the section is taken along the line 12—12 in Figure 13, which is itself a section taken along the line 13—13 in Figure 12.

Figure 14 is a section of a part, analogous to that shown in Figure 13, showing the members in a different position;

Figure 15 is a sectional elevation of a part, taken along a plane parallel to that of Figure 12, showing the members which actuate the distributor, and a projectile in position upon the receiving jaws before being sent down the channel which carries it to the loading trays or plates.

Figure 16 is a sectional elevation taken along the line 16—16 in Figure 15.

Figure 17 is a longitudinal sectional elevation of a detail showing a new projectile being carried on to the loading plates and on the point of engaging with the ramming breech block; the same figure shows a spent cartridge case secured to the ramming breech block which is locked in its extreme position of recoil.

Figure 18 is a corresponding plan section.

Figures 19, 20, 21 and 22 are sections of parts, taken along the lines 19—19, 20—20, 21—21, 22—22 in Figure 17.

Figure 23 is a sectional elevation analogous to that shown in Figure 17 showing the members in another position; the projectile is shown in the position it occupies at the 5 moment the movement for ramming it into the barrel of the gun commences.

Figure 24 is an analogous sectional elevation showing the projectile being rammed into the barrel, part of the projectile having 10 already passed into the bore of the gun.

Figure 25 is a corresponding plan section taken along the line 25-25 in Figure 24.

Figure 26 is a detail view partly in section illustrating one manner in which the 15 recoiling gun barrels may be operatively connected to the motion transmitting means for the cartridge conveyor.

In the general arrangement Figures 1 to 20 3, A is a gun carriage of any known type. A central pivot gun carriage which turns, in the known manner, on a platform A', has been shown in the example illustrated. B is the cradle of the gun carriage, which 25 pivots, by means of trunnions b, in the frame plates of the gun carriage A, the elevating and lowering of the gun being carried out by means of a known elevating mechanism which it is not necessary to describe.

30 For the purpose of description the invention has been assumed to be applied to two conjugated gun barrels C, D carried upon the same cradle B, the guns being so conjugated that the recoil of one of the barrels C causes the other barrel D to run out, the recoil of D conversely causing C to run out. The barrels may for example be conjugated in a manner disclosed in my application 35 Serial No. 429, filed January 3, 1925, allowed 40 May 25, 1925.

The loading apparatus is placed in an outer cover or casing E fixed to the cradle B; this apparatus comprises, in conformity 45 to the invention, an endless conveyor or chain of buckets or troughs the continuous movement of which is actuated by the alternate recoil and running out of the two conjugated gun barrels. The endless conveyor comprises two shafts F¹, F² turning in the 50 outer casing E, each shaft being provided with a pair of pinions (f¹, f² respectively) for carrying two endless chains. Each of the links F of one of the chains is connected to the corresponding link of the other parallel chain by cross members f. Upon each pair of cross stays f slides a bucket or trough G. The troughs of the conveyor actually form caps or holders for carrying the 55 projectile along. The fact of the troughs being able to slide along the cross stays f enables, as will be shown hereinafter, the projectiles to be displaced in the direction of their length while the movement of translation of the loader towards the distributor 60 is taking place. Each trough or holder G

65 consists of a sort of incomplete sleeve, provided at one of its ends with a semi-circular slot g in which engages the rim h of the cartridge case H (Figs. 13 and 15). One of the sliders g¹, g² with which the holder 70 G is provided for guiding it on the cross stays f, is provided with a pin on which is mounted a roller g³ which engages permanently with a fixed guide E¹ formed upon the outer casing E; this guide serves as a 75 guiding track for the trough shaped holders G during their longitudinal displacement when they thus move in the direction of their length by sliding along the cross stays f during the translational movement of the 80 chain.

Below the underside of the conveyor, the casing E is formed so as to receive, by hooking, a series of loading members or magazine 85 sections, each one containing a number of projectiles superposed on each other. The magazine section comprises for example, a channel I forming an arc of a circle and provided with a handle I¹; the lower part of this channel is closed by a bottom plate i¹ in which is formed a slot i² which engages with one of the spring locking devices e provided upon the casing E (Figs. 4 and 7); the upper part of each magazine section I is also provided with a flange i² by means 90 of which it engages behind the hook of a spring catch e¹ (Fig. 6). This catch is pivoted, in the case of one of the chambers containing the magazine sections, to the wall of the casing E; for the other sections, it is pivoted to the dividing walls E². Beneath each pile of projectiles is provided a plate J, attached to a shoe J¹, guided by the rollers j¹ in grooves e² forming circular arcs 95 provided upon the casing E, and upon the dividing walls E²; each plate is normally held in its lowest position, as shown in Figure 4, by a spring bolt J² with which it is provided, beneath a boss E³ formed upon the wall of the casing E or upon the dividing walls E². When the magazine section I is hooked upon the locking device e the spring bolt J² is pushed back and its end escapes from beneath the corresponding boss 100 E³. The plates are thus released so that they can move upwards at the desired moment, as described hereinafter, for the different projectiles in each pile to engage in the consecutive trough shaped holders of the 105 endless conveyor. 110

At the upper end of each section or channel I, is also provided a spring catch i³ which forms normally, under the action of its spring, a retaining means for the rim of the case of the projectile at the top of the pile. When the cartridge holder or channel I is hooked upon the casing E, the catch i³ presses against a flange e³ on the casing E, which forces it back and compresses its spring, so that the catch then 115 120 125 130

occupies the position shown in Figure 4, and releases the projectile at the top of the pile. This projectile is also held down by two cover plates K, carried by a shaft K¹, which turns in bearings provided upon the casing E and on the dividing walls E². At one of the ends of each shaft K¹ is provided an arm k¹, which engages with a catch k² provided at the end of a rod K² (Figs. 4, 6 and 10 11) guided, on the casing E or on the wall E²; the rod K² is pivoted to one of the ends of a link K³, the other end of which is pivoted to the casing E or to the wall E². The small link K³ is provided with a projection k³ (Fig. 4) against which presses an angle cleat j² provided beneath each plate J. 15

Each of the plates, J, J¹ guided, by its rollers j¹ upon the slideway e², also engages, by means of a fork provided upon its shoe 20 J¹ with a roller m the spindle of which is carried by a tubular slider M, which slides on a shaft L and is acted upon by a spring m¹ which continually tends to force it upwards. Each shaft L turns in bearings L¹, 25 L² carried by or provided upon the casing E, and receives its continuous movement of rotation from a bevel pinion L³. The latter is driven by a pinion L⁴ carried by a shaft L⁵ kinematically connected, by means of a 30 pinion L⁶ to a bevel pinion f³ carried by the shaft F¹ of the endless conveyor. The upper part of each of the shafts L is provided with a helical groove L⁷ for effecting the descent of the slider M, after the latter, by moving 35 upwards and carrying with it the corresponding plate J has emptied the corresponding magazine section I. The slider M will, for this purpose, be provided with a spring stud M¹, the end of which is guided 40 in a slideway E⁴ provided on the casing E (Figs. 4 and 5).

The projectiles are automatically transferred from the magazine to the distributor, which will be hereinafter described, in the 45 following manner:

The magazine sections I are hooked upon the casing E and to the dividing walls E², and, as mentioned above, this engagement between the flanged edges i² and the catch e¹ 50 on the one hand and between the slot i¹ and the locking device e on the other hand, effects the withdrawal of the catches i², which held the rim of the case of the projectile at the top of each pile, and also the spring bolts J² to be compressed, and as a consequence the several plates J to be released. The latter, however, will only be able to rise 55 in turn, under the action of each spring m¹ upon the corresponding slider M. When the gun is put into action, the extreme right hand slider is disengaged (Fig. 5), that is to say, the slider shown at the top in Figure 6 which was previously secured by means of the arm n of a spring catch N. At the lower 60 end of the catch N is provided a second arm n¹ which is continually held against the end of a rod N² sliding in the casing E, by the pressure of the spring N¹. If this rod is pushed in the direction of the arrow (Fig. 6), the catch N is made to turn about its 70 axis, and the arm n is withdrawn and thus releases the slider against which it pressed. The slider may then move upwards under the pressure of the spring m¹, drawing with it the corresponding plate J—J¹. As soon as the slider commences to move up, the projectile at the top of the corresponding section I lifts the covers K; this lifting is made possible by the rising of j², which enables the boss k³ to follow the movement. The top 75 projectile then engages in one of the trough shaped holders G of the conveyor, and is carried along, by being rolled upon the cover plates of the adjoining magazine chambers. The latter cannot empty themselves on account of the fact that the corresponding sliders M are each held in their lowest positions, by a spring catch O. 80

When it rises, by the rollers j¹ sliding in the guides e², the first plate on the right arrives at a point in its upward travel when the lowest projectile of the pile has engaged in the trough shaped holder which receives it as it passes over the top of that section. A projecting boss m² on the corresponding 90 slider M then meets an inclined plane o, provided upon the rod O¹ of the spring catch O—O¹, arranged so as to pivot in lugs e⁴, e⁵ provided upon the walls E² separating the chamber containing the first magazine section from the chamber containing the adjacent section. By climbing up the incline o the boss m² causes the rod O¹ to turn and, consequently, the catch O also, which releases the slider M, which it previously secured, so that this slider may in its turn, be forced up by its corresponding spring, and continue to feed the conveyor from the pile of projectiles contained in the corresponding section of the magazine. At the same 100 time, the first slider M having reached the top of its travel, the spring stud M¹ slips out of the guide channel E⁴ and its spring forces its other end into the helical groove L⁷, on the corresponding shaft L. The continuous rotation of this shaft, obtained as described above, effects the downward travel of the slider M. When the latter has reached a slightly lower position than the one shown in Figure 4, the end of the spring stud mounts the slope L⁸, provided at the point at which the helical groove L⁷ commences, and this forces it back and causes it to engage again in the guide channel E⁴. 110 At the same moment, the right hand slider M hooks itself again under the catch n. It is necessary to add that before the slider M and the plate J¹—J commence to descend, the plate, as soon as it arrives at the top of its travel, releases, by means of an 115 120 125 130

clined plane j^3 (Figs. 7 and 8), the catch e^1 which secures laterally, until this moment, the corresponding magazine section I. The weight of this magazine section which has 5 been emptied of its cartridges, causes it to swing by pivoting about the point at which it engages with the locking device e , and it is thus ejected. The corresponding chamber 10 of the casing is then ready to receive a duplicate section, while the adjacent magazine sections continued to feed the conveyor.

When a plate J^1 —J, after the emptying of the cartridge carrying section, has returned, as has been seen, to the bottom of 15 its travel, the projection j^2 encounters the boss k^3 upon the small link K^3 which causes a downward movement of the rod K^2 and consequent upon this, the cover plates or 20 arms K , for securing the cartridges in the chambers are lowered and brought into the desired position in order to retain the projectile at the top of that magazine section which has just been attached to the outer 25 casing E.

The second and the third magazine sections are emptied in the same manner as the first one; the fourth or last magazine section of the series (left hand section in Fig. 5), will in its turn be emptied by the action 30 of the corresponding tubular slider M. It will be noted that the corresponding rod O^1 of the spring catch O^1 —O is shorter than the preceding ones, in order that it will be struck by the corresponding boss m^2 of the 35 slider M before this slider has reached the top of its travel, which causes the corresponding catch n^1 to turn so that it will be moved out of the way, and automatically pushes the rod N^2 in order to release the first 40 right hand slider. The boss m^2 , as shown in the partial section in Figure 5, is provided with two planes inclined in opposite directions, as is the corresponding catch o , so that the latter will be automatically moved out of 45 the way, during both the upward travel and the downward travel of the slider.

The projectiles carried along by the conveyor reach in turn the stops E^5 , E^6 (Figs. 50 12 to 15), which prevent the projectiles from travelling any further with the conveyor, the corresponding holders or troughs G passing freely by these stops, due to the gaps g^4 , g^5 provided on the holder (Figs. 4 and 12). Thus stopped the projectile falls 55 upon receiving arms P, which are normally held raised by a torsion spring p coiled round their pivoting shaft, which turns in the casing E.

By rolling on to these arms P, the rim 60 h of the cartridge case being at the same time guided in a groove p^1 formed on the right hand arm (Fig. 12), the projectile falls on to receiving jaws Q turning upon shafts q carried by the casing E. These 65 jaws are normally held in the closed posi-

tion shown in Figures 12, 13, 15 and 16 by spring buffers Q^1 . The said jaws form a part of the distributor, by means of which the projectiles are alternately distributed to the right hand barrel and to the left hand 70 barrel of the arrangement of conjugated gun barrels. This distributor is completed by arms R carried upon a shaft R^1 , which turns in bearings provided upon the casing E. The shaft R^1 is given an oscillating 75 rotary motion, with a fixed amplitude. For this purpose there is keyed upon shaft R^1 and outside the casing E (Figs. 15 and 16), a slideway R^2 in which engages a roller r^3 which is carried upon the free end 80 of one of the arms R^3 of a swinging lever R^3 — R^4 which is pivotally mounted upon a shaft e^6 carried upon the casing E. The arm R^4 of the said swinging lever is provided at its free end, with a roller r^4 , which is guided in a cam groove f^3 formed in a plate F^3 keyed upon an extension of the shaft F^1 of the endless conveyor; the continuous movement of rotation of the shaft F^1 is thus transmitted, by means of the 85 swinging lever R^4 — R^3 as an oscillating movement to the shaft R^1 and the arm R which are mounted on the latter.

In this way these arms move alternately from the position shown in full lines in 90 Figure 16 to that shown in dot-and-dash lines in the same figure. In this movement, they carry with them the projectile which has been placed upon the pivoted jaws Q, which open as shown in Figure 14, the 95 weight of the projectile causing one of them to compress the corresponding spring buffer; in passing, the projectiles also push back the receiving arms P, which are then returned into their original position by the torsion spring at their hinges; the jaws which have opened are immediately returned into position for receiving another projectile (Fig. 13) by the corresponding 100 spring buffer Q^1 .

The projectiles, released alternately into the supply channels E^8 , E^9 formed in the casing E, are guided on to spoon shaped loading members or plates S which are pivotally mounted on a frame S^1 (Figs. 17, 18 and 19) which is guided on the frame plates of the cradle B, as is more particularly shown in Figure 18. The projectile upon reaching the loading plates S, is gripped by the spring buffers s lodged in the support of these plates and as the projectile passes to fall on to the loading plates it pushes the buffers back out of the way. It is also carried by the arms S^2 which consist of prongs 115 of a forked member, pivoted, by means of a shaft s^2 provided with a torsion spring, to the frame S^1 . The said frame is given an alternating upward and downward movement by a gear which is brought into play 120 when the gun runs out. The frame S^1 is 130

connected, for this purpose, by means of a stud S^8 , to one of the arms S^4 of a swinging lever S^4-S^5 (Figs. 17 and 21) pivoting about a shaft s^3 carried by the cradle B , the other arms S^5 of which lever is provided with a roller s^6 which engages in a cam groove s^6 formed in a plate S^6 , keyed to a shaft S^7 turning in the cradle. Upon this plate S^6 , is also formed a guide channel s^7 in which a pin C^1 projecting from the corresponding barrel C engages.

When the right hand gun is at the end of its recoil, the members occupy the position shown in full lines in Figures 17 and 18; the breech block C^2 which has carried back, gripping in its retaining groove c^2 , the spent case H , has become hooked behind a boss B^1 of the cradle B , by means of the spring locking device C^3 provided for example on the shaft C^4 of the running out recuperator.

The gun runs out, or "returns to battery," while the breech block is held back. Towards the end of this movement, which takes place during the recoil of the conjugated gun barrel, the cylindrical boss C^1 engages in the groove s^7 upon the disc S^6 , which causes the latter to turn on its shaft S^7 and the roller s^6 and consequently the swinging lever S^5-S^4 to be actuated by the cam groove s^6 . The arm S^4 of this swinging lever, as it descends, pulls down the stud S^8 , by means of a slot s^4 , and thus causes the frame S^1 to move down. During this downward movement, the forked member S^2 ejects the spent case H . At the end of the downward travel of the frame S^1 a fresh projectile is brought into the position shown in Figure 23, the axis of the projectile being in line with the axis of the gun, and the rim h of the case H being held in the groove c^2 . At the same time, a rod S^9 , pivoted to the cradle and provided with a roller s^9 which engages in the groove s^6 in the disc S^6 , turns about its pivoting axis and is brought into the position shown in Fig. 23, pulling with it, through the pivotal connection s^9 , a rod S^{10} , which actuates a lever S^{10} , keyed to a shaft S^{11} , which turns in the cradle B , and which is also provided with an arm S^{12} . By means of this arm the locking device C^3 which holds back the breech block is released, and the breech block can then be run out by the recuperator, and ram the projectile into the bore of the gun barrel.

As it moves towards the gun barrel, the breech block moves back the loading plates S , which pivot about the axis of their trunnions in the frame S^1 . The upper trunnions of the two loading plates are coupled together by a rod S^{13} and two small links s^{13} keyed to these trunnions, and this enables them to be withdrawn simultaneously. Upon an extension of the rod S^{13} is provided the spindle of a roller S^{14} . When the frame S^1 moves down the roller S^{14} moves along a ver-

tical guide B^2 provided upon the cradle B . When the loading plates are pushed back into the position shown in Figures 24 and 25, the roller S^{14} makes contact with the lower end of a guide B^3 also fixed to the cradle. 70

Towards the end of the running out movement, an arm C^5 provided upon the breech strikes a pawl S^{15} integrally mounted upon the disc S^6 , and thus causes the latter to swing round and the frame S^1 to move up, 75 at the same time as the loading plates S move back into position again to receive a new projectile as shown in Figures 17 and 19, due to the guiding of the roller S^{14} .

The breech block completes its running 80 out movement, in the known manner, as soon as the arm C^5 has brought the pawl S^{15} and the disk S^6 back into the position shown in Figure 17. As soon as the breech is closed the cap of the cartridge is automatically 85 fired in the known manner; the conjugated barrel has then completely recoiled, its breech block being locked upon the cradle, by means of the corresponding locking device C^3 . 90

Upon its recoil, the breech block carries the empty case H into the position shown in Figure 17, and the cycle of operations, which has been described above, recommences.

Any suitable device may be made use of 95 to rotate the conveyor of the leading apparatus continuously.

In order to translate the reciprocating motion of the conjugated barrels into a continuous rotation of the shaft F^1 of the conveyor, use may be made, for example, of the device described and illustrated in application Serial No. 429, hereinbefore referred to. 100

Figures 1 to 5 simply show a shaft T turning in the cradle of the gun carriage, and provided with helical grooves t and t^1 which are actuated successively by first one and then the other of the conjugated barrels, by means of sleeves U each provided with a tenon u engaging in a corresponding groove. 105 Each of these sleeves alternately turns in a boss C^6 attached to the corresponding barrel, and is locked to this boss. 110

When one of the barrels runs out, the groove t is actuated by the tenon u of the sleeve U , which is locked to this barrel, and causes the pinion V to rotate. 115

When the same barrel recoils, the sleeve U is released and no longer actuates the rotation of the pinion, but, during the same time, the running out of the other barrel ensures, through the actuation of the grooves t^1 the continuity of rotation of the pinion V the motion of which is transmitted, through the pinions W and W^1 , to the pinion f^4 keyed to the shaft F^1 of the conveyor. 120 125

Having now particularly described and ascertained the nature of my said invention I declare that what I claim is:—

1. Loading apparatus for guns comprising

ing an endless conveyor arranged substantially at right angles to the longitudinal axis of the guns and above the latter, means operatively connected with said conveyor 5 and guns for employing the energy of recoil and running out of the latter to actuate said conveyor, a magazine associated with said conveyor, members carried by the conveyor for receiving projectiles from the 10 magazine, a distributor for receiving projectiles from said members and for moving the projectiles into alinement with the bores of said guns, and means actuated by the recoil and running out of the guns for operating 15 said distributor.

2. Loading apparatus for guns comprising a casing, an endless conveyor therein including a pair of chains, cross stays connecting the links of one chain to the links of 20 the other, and troughs supported by said stays and slidable thereon, shafts rotatably mounted in the casing, movable cover plates operatively connected to said shafts, magazine sections in said casing, said cover plates 25 being adapted to move projectiles from said sections into said troughs, and means operatively connected to said conveyor and shafts and to said guns for employing the energy of recoil in running out of the guns 30 to actuate the conveyor and said cover plates.

3. Loading apparatus for guns comprising a casing, a conveyor therein, a magazine including a plurality of removable sections 35 associated with said conveyor and containing projectiles superposed on each other, means for attaching said sections to said casing, cover and guide plates for said sections, means for actuating said guide 40 plates including a shaft having a helical groove therein, a slider mounted on the shaft and having operative engagement with said plates, resilient means for moving said slider in one direction on the shaft, means 45 for rotating the shaft, and means carried by the slider and having engagement with said groove for returning the slider and cover plates to normal position.

4. Loading apparatus for guns of the 50 type that is automatically actuated by the recoil and running out of the guns, comprising a casing, a plurality of magazine sections removably mounted in the casing, plates operatively mounted in the casing for 55 supporting projectiles in the magazine sections, means normally locking said plates against movement, and catches engaging the top projectile in each of said sections, the insertion of the sections in said casing serving to disengage the plate locking means 60 and said catches.

5. Apparatus of the class described comprising a casing, a plurality of magazine sections carrying projectiles therein, means 65 for moving said projectiles out of said sec-

tions including a plurality of sliders movably mounted in the casing, means normally retaining said sliders against movement, manual means for releasing one of said sliders, means actuated by the manually released slider for releasing the remaining sliders in succession, the slider last released being adapted to automatically release the manually released slider.

6. Loading apparatus of the class described comprising a casing, a plurality of magazine sections therein, projectile moving plates for said sections, means for moving said plates, a plurality of shafts in the casing, cover plates for said sections secured to said shafts and normally preventing movement of the projectiles in the sections, and means operatively connected to said shafts and said projectile moving plates for returning the cover plates to normal position after the same have been rotated by movement of projectiles out of said sections.

7. Loading apparatus of the class described comprising a casing, a plurality of 90 magazine sections removably mounted therein, means normally locking said sections in the casing, said sections being adapted to fall away from the casing when released, movable plates for said sections adapted to engage said means, means for moving said plates to eject projectiles from the sections and to engage said first named means, the engagement of said plates with the latter serving to release the emptied sections.

8. An apparatus of the type wherein a plurality of gun barrels are so conjugated that the recoil of one of said barrels causes the other to run out and vice versa, and wherein breech ramming blocks are provided for automatically loading projectiles into said barrels, the combination with said barrels of an endless conveyor, a casing therefor, means connected to said barrels and conveyor for actuating the latter, projectile troughs operatively secured to the conveyor, stops for removing projectiles from said troughs, spring jaws for receiving the projectiles, releasing arms for guiding the projectiles from the troughs to said spring jaws, means for moving projectiles from said jaws to a point above the longitudinal axes of said barrels, a frame movably mounted on the casing, means for moving said frame, loading members mounted 110 on the frame and adapted to receive projectiles from said jaws, and means secured to the frame for ejecting spent cases.

9. Apparatus of the class described comprising, in combination with a pair of conjugated guns, an endless conveyor mounted above said guns, means operatively connected with said conveyor and guns for employing the energy of recoil and running out of the latter to continuously actuate said

conveyor, a magazine formed of a plurality of sections associated with said conveyor, members carried by the conveyor for receiving projectiles from each of the magazine sections in succession, distributor means for receiving projectiles from said members and for moving the projectiles into aline-

ment with the bores of said guns, and means actuated by the movement of the guns for operating said distributor.

10

In testimony whereof I have signed this specification.

NICOLAS EMILIEN METHLIN.
